BEDSPRING

Louis I. Cohn, Philadelphia, Pa.

Application September 10, 1940, Serial No. 356,213

2 Claims. (Cl. 5—250)

This invention relates to an improved bed spring.

An object of this invention is to provide an improved bed spring wherein the component parts thereof are coated with a rubber or rubberized coating which will serve not only as a protective covering for the metal parts to prevent corrosion, but also to eliminate noises caused by shifting or movement of the parts and to fill all cracks to prevent hiding of vermin.

Another object of this invention is to provide a spring which is formed in sections including a main or body section, a head section and a foot section, the sections being hingedly secured together so that the sections may be individually easily handled by one person.

A further object of this invention is to provide a spring including a main resilient body section, a head section, and a foot section, the head section being so constructed that it may be disposed at an angle relative to the body section.

A still further object of this invention is to provide a spring of this character wherein the foot section is formed as a compartment to receive bed clothes or the like.

A further object of this invention is to provide a spring of this type wherein the main body section is formed of opposed pairs of springs of different resiliency so that one side may be used for a light weight person, or the spring may be turned over for use of the opposite side by a heavy person.

A further object of this invention is to provide a spring structure formed of helical springs which are hingedly secured to the frame structure.

A further object of this invention is to provide a sectional spring unit in which one section is formed with an inner spring construction which is covered with a coating, such as rubber or rubberized material, the spring construction being either dipped into or sprayed with the coating material.

In the drawings:

Figure 1 is a top plan partly broken away and in section of a bed spring structure constructed according to an embodiment of this invention.

Figure 2 is a longitudinal section taken substantially through the central of the spring structure.

Figure 3 is an enlarged fragmentary transverse section through the body of the spring structure.

Figure 4 is a sectional view taken on the line 4—4 of Figure 1.

Figure 5 is a fragmentary sectional view taken on the line 5—5 of Figure 1.

Figure 6 is a fragmentary sectional view taken on the line 6—6 of Figure 1.

Figure 7 is a sectional view taken on the line 7—7 of Figure 1.

Figure 8 is a sectional view taken on the line 8—8 of Figure 2.

Figure 9 is a fragmentary sectional view taken on the line 9—9 of Figure 1.

Figure 10 is a sectional view showing the hinged connection between the inner or main spring body and an end section, and

Figure 11 is an enlarged fragmentary sectional view taken on the line 11—11 of Figure 6.

Referring to the drawings and first to Figures 1 to 11, inclusive, the numeral 20 designates a spring body section, the numeral 21 designates a non-resilient head section and the numeral 22 designates a non-resilient foot section.

The three sections 20, 21 and 22 form a single spring structure which is adapted to be mounted in a bed and upon which a mattress not shown is adapted to be mounted.

The body spring structure 20 comprises an upper rectangular frame member 23, a lower rectangular frame member 24 and an intermediate frame member 25. The spring structure 20 includes a plurality of opposed pairs of helical springs 26 and 27, the springs 26 being formed of heavier material than the springs 27 and these springs are arranged with their small ends in opposed relation. The springs 26 which are outermost are adapted to be swingably secured to

the frame member 23 by cutting an arcuate recess 28 in the inner side of the frame member 23 so that the base convolution 29 of the spring 26 may engage within the recess 28. The material forming the frame member 23 is then bent inwardly sufficiently so that the upper convolution 29 of the spring member 26 will be loosely held within the recess 28. The inner series of springs 26 are tied together by crossed tie bars 30 which are formed at their opposite ends with

loops or hooks 31 which engage about the upper convolutions 29 of the springs 26.

A plurality of transversely extending parallel intermediate frame bars 32 are disposed within the intermediate frame member 25. The frame bars 32 are disposed in edgewise relation and at their opposite ends the frame members 32 are twisted as at 33 and then extended over the intermediate frame member 25. Each frame bar 32 is then formed with an L-shaped extension 34 which is provided with a vertical outer leg 35.

A spring supporting bracket or arm 36 of L-shape is adjustably secured to the vertical leg 35 by means of a thumb bolt 37. The bracket or hanger member 36 is formed with an outwardly extending upper leg 38 which is adapted to engage over the edge of a bedstead. The bracket member 36 may be formed with an elongated slot 39 through which the thumb bolt 37 engages so that the bracket member 36 may be vertically adjusted in order to adjust the height of the spring member 20 or to adjust the angular relation of the spring member 20 to the horizontal. The transverse tie bars or frame members 32 are formed in their upper edges with a pair of notches 40 within which the apex or lower convolution of the spring 26 is adapted to engage. The bar 32 is also formed with an opening 41 below the upper edge thereof and the free end 42 of the spring 26 is adapted to be threaded into the opening 41.

A plurality of longitudinally extending tie bars 43 are disposed in parallel relation relative to the sides of the intermediate frame member 25. The tie rods 43 are round in transverse section and are also extended through the openings 41 of the flat transverse tie bars 32. The opposite ends of the longitudinal tie rods 43 may be welded or otherwise fixedly secured to the opposite ends of the intermediate frame 25. The bars 32 and rods 43 correlate to form a grid structure or element which is supported by the frame 25.

The helical springs 27 are disposed in reversed position to springs 26, the lower springs 27 having the lower convolutions 44 thereof secured to the lower frame member 24 in the same manner as the spring convolutions 29 are secured to the upper frame members 23. The lower spring members 27 have their lower convolutions 44 tied together by means of a plurality of crossed tie bars 45. The tie bars 45 are similar to the tie bars 30 and may be formed either from a single piece of material which is stamped out in the form of radially arranged arms having loops at their opposite ends as shown in Figure 9 or the tie bars 45 may be formed in overlapping crossed bars.

The transverse tie bars 32 have formed in their lower edges pairs of notches 46 in which the upper convolution 47 of each coil 27 is adapted to engage. The bars 32 are also formed with an opening 48 through which the end 49 of the spring 27 is adapted to be threaded. As shown in the drawings, the spring structure 20 is adapted to be coated completely with a rubberized coating. The frame structure 23 as shown in Figure 10 is coated with a rubberized coating 50 and the springs 26 are also coated with a rubber or rubberized coating 51. In like manner the transverse tie bars 32 are coated with a rubber or rubberized coating 52 and the lower frame structure together with the lower springs and crossed tie bars 45 are adapted to be coated with a rubberized or rubber coating. In this manner, the spring structure 20 will be noiseless and in addition the rubberized coating will prevent corrosion from affecting the metal forming the spring structure.

The bracket or hanger members 36 may also be covered with a rubber or rubberized coating so that these members will not injure the bedstead and in addition in the event there is any movement between the hangers 36 and the bedstead, this movement will be cushioned and the noise of movement will be deadened by the rubber coating on the hangers 36. The head mem-

ber 21 comprises a rectangular-shaped frame including an outer frame bar 53, an inner frame bar 54 and side frame bars 55. The frame bars 53, 54 and 55 may be made from a single length of material such as a round bar or the like which may be bent in rectangular form and the ends thereof welded together.

The end members 53 and 54 have secured thereto between the sides 55 a plurality of flat straps 56. The straps 56 are adapted to be extended into openings or channels 57 which are formed in the inner edge portion of the end member 53 and into openings or channels 58 formed in the confronting edge of the rear end member 54. The straps 56 may be welded or otherwise fixed within the recesses 57 and 58. The side frame members 55 have secured thereto in dependent relation a depending arm 59 and an L-shaped bracket member 60 is adjustably secured to the arm 59 by means of a thumb bolt 61. The bracket member 61 has formed in the vertical leg 62 thereof an elongated slot 63 through which the bolt 61 engages.

The horizontal leg 64 of the bracket or hanger 60 extends right angularly and outwardly from the vertical leg 62 and is adapted to engage either the upper edge of the bedstead or may engage a ledge or flange formed interiorly of the side boards of the bedstead. The head member 21 is hingedly and detachably secured to the head end of the frame 20 by means of a pair of hinge straps 65. The straps 65 are formed with an arcuate portion 66 engaging about the inner end member 54 of the head frame 21 and the arcuate portion 66 is adapted to be welded or otherwise fixed to the end member 54. Each strap 65 is formed with an arcuate hook 67 which loosely engages about the adjacent end of the frame member 23 so that the head member 21 may be angularly adjusted with respect to the spring structure 20. The frame structure 21 is formed with a rubber coating 68 and in like manner the hinge straps 65 are also formed with a rubber coating 69. The webbing bars or straps 56 may also be coated with a rubber coating and in like manner the depending straps or bars 59 and the bracket member 60 may also be coated with rubber or other yieldable covering.

The foot section 22 is constructed similar to the head section 21 with the exception that the foot section 22 is longer than the head section 21. The foot section 22 comprises an outer end bar 70, an inner end bar 71 and opposite side bars 72. The bars 70, 71 and 72 may be formed from a single length of round metal which is adapted to be bent in rectangular shape and the confronting ends thereof welded or otherwise fixed together to form a rectangular foot section. The rectangular frame formed by the end members 70 and 71 and side members 72 is provided with a plurality of parallel straps or webbing members 73 which are extended into openings 74 in the end member 70 and are also extended into openings 75 in the end member 71. The foot section 22 is hingedly secured to the spring structure 20 by means of a pair of hinge straps 76 which are constructed similar to the hinge straps 65. The foot section 22 is adapted to be coated with a rubber coating similar to the spring structure 20 and the head section 21. The foot section 22 on the opposite sides 72 thereof has secured thereto a depending arm 77 to which an L-shaped supporting or bracket member 78 is adapted to be secured by means of a thumb bolt 79. The bracket member 78 is formed with

a vertical leg 80 having an elongated slot 81 therein through which the bolt 79 is extended. The horizontal leg 82 of the bracket 78 is lowermost and extends outwardly from the side members 72. The horizontal legs 82 of the bracket or supporting members 72 are adapted to engage a ledge formed on the side rails of the bedstead or may be engaged with the upper edges of the side rails. By providing an adjustable supporting structure 78 for the foot section 22, the angular relation of the foot section 22 with respect to the upper surface of the spring section 20 may be easily and quickly adjusted so that this spring structure may be used as a hospital spring where the foot section is raised relative to the intermediate or body section. In like manner the head section 21 may be inclined upwardly for reading or other purposes.

The head section 21 and the foot section 22 are adapted to be disposed in the same plane as the upper frame structure 23 of the spring section 20 when the spring structure is in normal use. In this position of the head section 21 and the foot section 22, there will be a considerable space between the under faces of these two sections and the lower portion of the spring structure 20. In order that at least one of these spaces may be utilized, I have provided a receptacle generally designated as 83 which in plan is of rectangular configuration substantially the size of the foot section 22. The receptacle 83 is constructed in the form of an open basket and comprises an upper rectangular frame 84, a lower rectangular frame 85 and an intermediate rectangular frame 86. A plurality of vertically disposed side bars 87 are secured to the side members of the upper and lower frame members 84 and 85 and a plurality of vertically disposed end connecting bars 88 are connected to the forward and rear portions of the frame members 84 and 85.

The intermediate frame 86 is disposed on the inner sides of the vertical bars 87 and 88 being welded or otherwise fixed thereto. The receptacle 83 is adapted to be completely coated with rubber or rubberized material 89 and the receptacle 83 is supported beneath the foot section 22 independently thereof by means of pairs of side supporting or hanger members 90 which extend laterally from the sides of the upper frame member 84. A vertically disposed and downwardly extending bar 91 is formed integral with the horizontal supporting member 90 and the vertical bar 91 is extended as at 92 beneath the bottom of the receptacle 83. In practice the bottom bar 92 is bent in substantially U-form with the bight 92 extending across the bottom of the receptacle 83 and the parallel legs 91 are disposed in the opposite sides of the receptacle 83 and the terminal ends of the legs 91 are bent outwardly as at 90 so as to form receptacle supporting means which are adapted to engage over the upper edge of the side rails of the bedstead.

The spring structure shown in Figures 1 to 11, inclusive, is adapted to be mounted in a conventional bedstead and in normal use the upper

surface of the spring structure will be substantially horizontal. The supporting legs 60 for the head section 21 are adjusted to dispose the head section 21 in a horizontal position and the supporting legs 78 are also adapted to be adjusted to position the foot section 22 in a horizontal plane. However, in the event the head section 21 has to be raised or inclined to the horizontal for reading or other purposes, the leg member 60 may be lowered so as to extend the foot 64 thereof. This will have the effect of changing the angular relation of the head section 21 relative to the body section 20. If desired the body section 20 may also be inclined to the horizontal by adjusting the leg members 36. Preferably a mattress similar to that shown in Figures 12 to 15 is used in combination with this spring structure so that the several sections of the spring may be adjusted relative to an adjacent section and so that the other side of the spring structure may be cleaned.

The receptacle 83 may be used with the spring structure hereinbefore described and may form a convenient storage space for bed clothes or other articles. Where the spring member 20 is to be used by a relatively heavy person, the heavier springs 26 are disposed in an uppermost position with the lighter springs 27 lowermost. However, where a light weight person uses the spring structure, the spring member 20 may be reverted so as to position the lighter springs 27 uppermost. This may be accomplished by unhooking the hinge hooks 65 and 76 which are carried by the head and foot sections respectively and then hooking these hooks onto the lower frame structure 24. The rubber coating which is placed on all the parts of the spring structure hereinbefore described may be placed thereon by either dipping the spring structure in rubber solution or spraying the solution on the spring structure.

What I claim is:

1. A sectional bed spring comprising a central resilient section, a non-resilient head section hingedly secured to one end of said central section, means for adjusting the angular relation of said head section with respect to said central section, a non-resilient foot section hingedly secured to the other end of said central section, and a storage basket, said foot section having a storage compartment therein, and said storage basket being adapted to removably slide within said storage compartment.

2. A sectional bed spring comprising a central resilient section, a non-resilient head section hingedly secured to one end of said central section, a non-resilient foot section hingedly secured to the other end of said central section, and a storage basket adapted to be mounted within said foot section, said foot section comprising a rectangular box-like frame work having an open top, said basket being adapted to slide within said foot section through said open side of said foot section.

LOUIS I. COHN.
